(74) Attorney, Agent, or Firm—Townsend and Townsend and Crew

(57) **CLAIM**

The ornamental design for a portable telephone, as shown and described.

DESCRIPTION

FIG. 1 is a top perspective view of a portable telephone showing my new design;
FIG. 2 is a top plan view thereof;
FIG. 3 is a bottom plan view thereof;
FIG. 4 is a front elevational view thereof;
FIG. 5 is a rear elevational view thereof;
FIG. 6 is a left side elevational view thereof;
FIG. 7 is a right side elevational view thereof; and,
FIG. 8 is a perspective view in an open condition thereof. The portions of the article not shown in the drawing or described in the specification form no part of the claimed design.
